UNITED STATES PATENT OFFICE

FRANK LESINSKI, OF BROOKLYN, NEW YORK

SHOEMAKING

Application filed December 27, 1929. Serial No. 416,887.

This invention relates to the art of making shoes and has for its broad object to provide an improved method of assembling the heel and sole of a shoe.

5 The principal object of the present invention is to provide an improved method of attaching the sole and heel of a shoe which greatly simplifies the labor and reduces the time necessary to properly assemble the heel and sole in their proper relationship.

10 Other objects and advantages of the invention will be hereinafter specifically pointed out, or will become apparent, as the specification proceeds.

15 With the above indicated objects in view, the invention resides in certain novel constructions and combinations and arrangement of parts, clearly described in the following specification and fully illustrated in the accompanying drawings, which latter show embodiments of the invention as at present preferred.

In said drawings:

20 Figure 1 is a perspective view illustrating a heel, a top-sole and an outer sole in assembled position preparatory to attaching the rear or heel end of the outer sole to the breast of the heel.

25 Figure 2 is a side elevation of a heel and sole assembly showing the manner of placing the outer sole in intimate contact with the heel ready for marking the position in which to place the cutting tool. The broken lines indicate the position of the cutting block and tool when trimming the rear end of the heel.

30 Figure 3 is an elevation illustrating the appearance of the finished heel after the outer sole has been glued in place and the rubber or leather heel fastened in place.

35 Figure 4 is a plan view of a cutter for producing the desired outline in the outer sole to match the outline of the edge of the breast of the heel.

40 Figure 5 is a longitudinal section on the line 5—5 of Figure 4.

Figure 6 is a transverse section on the line 6—6 of Figure 4.

45 Figure 1 shows say a lady's shoe as built up preparatory to applying the method and devices of the present invention; the shoe

including a sole-tap 7 to which is secured a heel 8, the heel being customarily made of wood while the sole-tap is preferably made of leather. The sole-tap 7 is split as at 9 and the tapering edge so formed is glued to the lower edge surface of the breast of the heel. Preparatorily there has been partially secured to the top surface of the sole-tap 7 a relatively thinner outer-sole 10. So far the construction has been in accordance with the present practice, in which the rear portion 11 has been made larger than necessary to cover the breast of the heel in order to allow for trimming the outer sole to the contour of the breast.

55 Figure 3 indicates the result it is desired to obtain, in which the extreme terminal portion of the enlarged end 11 has been turned over the upper edge of the breast of the heel and nailed in place, the enlargement 11 having been previously trimmed to the contour of the edges of the breast and then glued in place.

60 Under present methods a finished job, of course, is only had, and a finished job is necessary, when the terminal portion 12 is skived to a tapering thinness as shown in the figures and when the sides 13 of the flap are trimmed as at 14 to match exactly the side edges of the heel breast, and, finally, when the portion 11 is cut to an outline exactly that required before skiving the portion 12.

65 The present method of attaining the above result is both awkward and time consuming to say the least. Trimming the enlarged portion 11 of the rear end of the outer sole cannot be done while the flap 11 formed by the free end of the outer sole is against the breast of the heel for fear of marring the heel. In order to trim the outer sole to conformity with the outline of the edges of the breast the flap must first be held against the breast of the heel as in Figure 2 and a pencil used to outline the cut to be made, then there

70 must be performed a bending back of the flap and a trimming of the outline 13 with a sharp knife. This procedure is slow and tedious and furthermore does not always produce the sharp outline desired nor does it always 75

match the edges of the breast exactly when the flap is finally glued to the heel breast.

The procedure just outlined has been simplified and the time to perform the process of shaping the flap reduced considerably by providing cutters or dies 15 adapted to produce the desired outline conveniently and quickly. The cutters 15 are formed preferably of tempered steel and are equipped with a sharp edge 16 ground fine enough to readily pierce the leather when suitable pressure is applied as by a blow of a hammer. The cutters are shaped substantially as indicated in Fig. 4 and the cutting edge is so formed as to conform exactly to the outline which must be produced in the flap 11 in order to have the flap match the edges of the breast of the heel. For each size of heel naturally enough a separate cutter must be provided having a contour of cutting edge adapted to the heel which is to be used.

The cutters 15 are used in the following manner: After the parts had been primarily secured together as shown in Fig. 1 preparatory to trimming to fit the contour of the edges of the breast, the flap is arranged as shown in Fig. 2 and a scribe or pencil is used to mark the upper extremity of the desired cut, the wooden or leather heel having been first held in position; the final close pressed location of the extremity of the flap and the corners of the heel being indicated, a wood or brass block or anvil 18 is then arranged in place on the surface of outer sole 10 and the flap 11 is laid flat against the top surface of the block as indicated diagrammatically in dot and dash lines in Fig. 2. Then the cutting tool is laid down, the cutting edge lowermost, on the surface of the flap 11 as shown in Fig. 2 and carefully placed so that predetermined portions of said tool and marks thereon have a predetermined relation to the marks made by the pencil. A sharp blow is then struck on the tool as, by means of a hammer, driving the cutting edges of the tool into the leather thus severing the leather with an outline conforming to the shape of the tool. The block 18 and the tool 15 are now removed and the terminal portion 12 is skived to a knife edge. The flap 11 is now glued firmly to the surface of the heel breast and will be found to conform exactly to the contour of the edges of the breast. The rubber or leather tap 17 having been previously removed the terminal portion 12 is bent over and tacked in place after which the tap 17 is fastened in place by means of suitable nails or studs.

The whole operation just described takes but a moment or two to be performed and when completed the edges of the flap will be in exact conformity with the contour of the edges of the heel breast. It will be clear therefore that the process herein disclosed

provides a ready and rapid method of producing the desired outline in the flap 11 and avoids the tedious and laborious operation of first outlining the desired cut by means of a pencil and then cutting the outline by means of a knife. The only trimming or cutting involving the use of a knife is the skiving of the terminal portion 12 and possibly a slight amount of trimming which may be required at the narrowest portion of the outer sole which, when the shoe is being worn, underlies the instep of the foot. It will therefore be seen that no trimming involving the use of a knife is necessary along the edges of the outer sole which conform to the edges of the wooden heel with the result that there is no danger of marring the heel. It will be clearly seen that trimming by means of a knife along the narrowest portion of the insole may be accomplished without serious danger of marring the sole since the knife may be most efficiently handled at this point.

The hereinbefore described method, admits of considerable modification without departing from the invention; therefore, it is the wish not to be limited to the precise arrangements shown and described, which are as aforesaid, by way of illustration merely. In other words, the scope of protection contemplated is to be taken solely from the appended claims, interpreted as broadly as is consistent with the prior art.

What is claimed as new, is:

1. In the art of manufacturing shoes in which a heel structure and a sole structure have been preparatorily and partially secured together in readiness for finishing, the method of finishing the heel structure which involves placing a free flap of the sole structure in a second position in contact with the breast of the heel, said second position being a close approximation of the position the flap will occupy in relation to said heel breast when the heel structure is completed, then marking an indicium on said flap to constitute an index to a substantially U-shaped outline with the sides of the U conforming substantially exactly to the side edges of said heel breast, transferring said flap from said second position to a cutting position, then cutting said U-shaped outline from said flap substantially simultaneously in all parts of said outline, and finally fastening the flap to the breast of the heel.

2. In the art of manufacturing shoes in which a heel, and a sole structure have been preparatorily and partially secured together in readiness for finishing, the method of finishing a shoe which involves placing the free flap of the sole structure in a scribing position in contact with the breast of the heel, scribing said flap to define an outline conforming substantially to the side edges of said heel breast, locating temporarily a substantially flat support atop said sole struc-

ture, transferring said flap to overlie said support and to lie flatwisely thereon, applying over said flap a cutting die having a cutting edge conforming to said outline, arranging said die so that its said edge matches said outline, operating said die to drive the cutting edge thereof through said flap substantially perpendicularly therethrough thereby to cut a complete outline at one operation 10 pursuant to such scribing, and fastening the flap to the breast of the heel.

3. In the art of manufacturing shoes, the method of assembling a heel and a sole structure, which involves partially securing said 15 sole structure to the heel structure, providing a sole flap and placing in contact with the breast of said heel structure, indicating a reference point on said flap, removing said flap from contact with said heel portion, placing 20 said outer sole in a position for cutting a predetermined outline, providing die and anvil elements the former of which has a cutting edge conforming to said outline, arranging said elements to locate said flap there- 25 between, operating said elements to cut said outline while guided by said point, and then securing said flap to the breast of the heel.

In testimony whereof I hereby affix my signature.
